UNITED STATES PATENT OFFICE

RICHARD BÄRWOLF, OF GERA, GERMANY

GAS COOKER

Application filed September 7, 1928, Serial No. 304,519, and in Germany December 17, 1927.

This invention refers to a new construction of gas cooker, the novelty of which is based on the arrangement of a support for the burner on the frame of the gas cooker, on the 5 one hand, and on the other hand the invention relates to a special construction of the burner itself.

According to this the burner is arranged interchangeably in a support which can easily 10 be taken out of the gas cooker or frame. This is of a special advantage in cleaning or renewing any part of the burner, as the parts can be easily removed or replaced as desired.

The support receiving the burner is interchangeably arranged on the gas cooker in such a way that one end of a slide is formed 15 into a ball which is inserted into a double bearing, fixed to the gas cooker, and in such a way that it may be swivelled in any plane, 20 while the opposite end of this slide is fastened simply on the gas cooker either directly or indirectly with intermediate gear bearing arm, being detachable, so that the supporting-slide may be removed from the gas 25 cooker immediately either with the burner or without. The burner will give a fan like cooking-flame on account of the special construction and arrangement of each part to the other, which forms an inner and an outer 30 flame, giving a broad fan like cooking-flame, or through interchanging in taking off or exchanging the upper burner lid, a cone-shaped or wedge-shaped flame will be produced.

35 In the drawings:

Fig. 1 is a section through the gas cooker.

Fig. 2 is a top view.

40 Figs. 3, 4 and 5 are single views of the burner,

Fig. 3 being a top view of the distributor plate 17,

Fig. 4 a similar view on a smaller scale, and

45 Fig. 5 a vertical section through the burner proper.

Fig. 6 is another construction of the burner.

Figs. 7 and 8 are single views of the same,

Fig. 7 being a top view of the plate.

50 Fig. 8 is a similar view of the multiplied form of distributor on a smaller scale.

Fig. 9 shows a section through another construction of the support, and

Fig. 10 is a top view of the same.

On the frame 1 of the gas cooker is secured 55 the double bearing 2 which receives the pin 5 of the gas cock 6 at the outer plane; the gas supply-pipe 11 being in connection with gas cock 6 is loosely fitted in an extension of the fork bearing 9, and at the same time is interchangeable with the gas cock 6 after loosening 60 the screw 5^a on pin 5.

The supporting slide 3, 7 is interchangeable and, for this purpose, the arm 3 is formed 65 into a ball 4 at one end, which forms a ball-bearing in connection with the inner half of the double bearing 2, and thus allows a movement of the supporting-slide with the burner.

Arm 7 of the supporting slide 3, 7 is situated in the fork-bearing 9, and the supporting slide is secured by means of an extractable pin 10. 70

In the middle of the supporting slide 3, 7 a circular hole 12 has been provided for receiving the burner 8 with slots 13 for leading the lateral pin 8^b through. 75

The burner 8 which is open at the bottom and stands vertically is interchangeably situated in a hole 12 of the supporting-slide 3, 7 and is provided with a circular collar 8^a, and under the same is provided with a lateral pin 8^b which in connection with the circular collar 8^a resting on the supporting slide 3, 7 forms a bayonet joint for the burner 8. The burner 8 can also be firmly connected with the arms 3 and 7, whereby the interchangeability is secured owing to the two parallel supporting arms 3 and 7, lying in a longitudinal direction. 80

According to Figs. 9 and 10 the central section of the supporting slide 3, 7 with the circular hole 12 is connected with ribs 14 acting 90 as supporting arms, which are exchangeable in an adjustable way or these may be firmly connected with frame 1 of the gas cooker or with the heating-plate. The under part of the burner 8 is provided with a rim 12^a which is designed to receive the overflow while cooking and will serve to keep the burner clean. 95

The burner 8 is constructed in such a way 100

as to form an inner and an outer burner independent of each other, and either acting as cooking-burner or heating-burner. According to Figure 1 of the drawings the burner-lid 17 which is put on the burner head 16 is provided with holes in order to obtain a fan like cooking flame. At the same time an inner burner is also formed in such a way that a plate 19, or the perforated hood 20, 10 which are situated around the mixing-pipe 18, cover the mixing-space 21. Plate 19, Fig. 5, and hood 19^a are arranged interchangeably. If the burner-lid 17 is removed the flame may be lit at the inner burner, when 15 it burns, forming a cone-shaped or wedge-shaped flame, which will burn vertically. The plate 19 covering the lower part of the mixing space is situated on the periphery of the burner pipe by means of fingers at 19^a, 20 and the lid 17, in Figures 6 and 9 is conically inclined upwards to the centre (Fig. 9).

In the burner lid 17, as well as in plate 19, or hood 20 which are situated inside the burner-head there are slotted openings 22 25 from the edge towards the central axis however not reaching quite as far as the centre, which serve for forming the wedge-shaped heating flame which will burn vertically. Owing to the special arrangements of these 30 slits 22, a distributor-plate 23 is formed on burner lid 17, plate 19 or hood 20.

The hood 20 may also be formed so as to be able to exchange the inner parts of the burner easily, into a case 24 and a plate 19 35 fixed into the same, (Fig. 5).

According to Figure 6 the burner is constructed in such a way that in order to change the form of the flame only the upper lid of the cooking-burner 17 has to be removed. 40 For this purpose an interchangeable-lid 23, is used which is provided with slits 22 to produce a cone-shaped or wedge-shaped flame, which will burn vertically which plate is inserted interchangeably as a heating- 45 burner on the burner-covering 16 (see Fig. 5) between the plate 19 and the lid of the cooking-burner 17, whereby the outer edge 26 is constructed as burner-head, and also forms at the same time the burner head for the lid 17 50 of the cooking-burner.

The plate 23 is provided with slits 22 for the passage of the gas, and may be situated interchangeably on the extension 26 of the burner-covering 16, under the intermediate 55 lid 25, thus forming a heating-burner.

What I claim is:

1. A gas cooker composed of independent sections adapted for use as either cooking burner or a heating burner, a removable hood 60 and a plate interchangeably related with reference to each other, and a burner cover, said burner cover being formed with openings for the purpose stated.

2. In a gas cooker, a supporting slide having arms, a ball bearing for one of the arms,

and means for supporting a burner intermediate said arms.

3. A gas cooker in accordance with claim 2 in which the other arm is supported in a fork bearing. 70

4. In a gas cooker, a slide having arms, one arm having at one end a ball bearing and at the other end a fork bearing.

5. A gas cooker in accordance with claim 4 in which the fork bearing carries a removable member for holding the slide in adjusted position. 75

6. A gas cooker and a burner having inner and outer sections, each adapted to serve independently of each other, and a supporting member having a ball support at one end and an adjustable support at the other end. 80

7. A structure in accordance with claim 6 in which the supporting member has an opening for the detachable support of a 85 burner.

8. A gas cooker composed of independent sections adapted for use as either a cooking burner or a heating burner, a removable hood, and a plate, the two last-named elements being interengagingly related, and a lid, the latter being provided with openings, to produce a wedge-shaped flame. 90
